Primary Examiner — Daniel J Domino

(74) Attorney, Agent, or Firm — Patterson Thuente
Pedersen, PA(57) **CLAIM**

The ornamental design for a display screen with graphical user interface, as shown and described.

DESCRIPTION

The FIGURE is a front view of a display screen with graphical interface showing the new design.

The broken lines showing a medication dispenser illustrate environmental subject matter, whereas the broken lines showing a display screen and elements of the graphical user interface illustrate portions of the article. None of the broken lines form part of the claimed design.
